US00D518467S

(12) **United States Design Patent** (10) **Patent No.:** **US D518,467 S**
Kim et al. (45) **Date of Patent:** **** Apr. 4, 2006**

(54) **CELLULAR PHONE**

(75) Inventors: **Jong Kyu Kim**, Seoul (KR); **Yoon Young Cho**, Seoul (KR); **Jong-Seong Lee**, Seoul (KR)

(73) Assignee: **Samsung Electronics Co., Ltd.** (KR)

(**) Term: **14 Years**

(21) Appl. No.: **29/221,390**

(22) Filed: **Jan. 15, 2005**

(30) **Foreign Application Priority Data**

Jan. 3, 2005 (KR) 30-2005-0000044

(51) **LOC (8) Cl.** **14-03**

(52) **U.S. Cl.** **D14/138**
